UNITED STATES PATENT OFFICE

OLIVER MORGAN AND JOHN W. STAERK, OF WEWOKA, OKLAHOMA

VALVE FOR OIL-DISTRIBUTING SYSTEMS

Application filed April 18, 1929. Serial No. 356,080.

This invention relates to improvements in valves for oil distributing systems, and has for its primary object the provision of a valve unit embodying certain improvements over the valve shown and described in our co-pending application, Serial No. 313,802, filed October 20, 1928.

The improved features of the present valve over the structure embodied in our co-pending application, are namely the valve float operating mechanism, the protecting cover, the wrench means for removing the valve seat, as well as other novel modifications.

Other important objects and advantages of the invention reside in the provision of means for positively operating the valve, to protect the valve during inclement weather and facilitating its disassembly for the purpose of repair or replacement.

These and other objects of the invention will become more apparent to the reader after considering the invention as described and claimed hereinafter.

In the drawings:

Figure 1 represents a vertical sectional view through the novel structure.

Figure 2 represents a horizontal sectional view.

Figure 3 represents an edge elevation of the valve plate.

Figure 4 is a side elevation of the wrench.

Figure 5 is an end elevation of the wrench.

Figure 6 is a side elevation of the cover.

Figure 7 is a top plan view of the cover.

Referring to the drawings, wherein like numerals designate like parts, it will be seen that the improved structure as set forth in our co-pending application includes a cylindrical body 7 constructed to provide an upper and a lower chamber 8 and 9, which communicates through a renewable valve ring 10.

The lower chamber 9 is equipped at its upper end with the usual inlet nipple 11, within which, in the present instance, is a strainer screen 11'. The upper chamber is equipped with an outlet nipple 12 and this communicates with the chamber 8.

An improved bonnet structure generally referred to by numeral 13 has the valve stem 15 slidably disposed therethrough

which also extends downwardly within the lower chamber and through a renewable valve seat ring above the spider 14. Secured to the valve stem 15 and between the valve seats 10 and 16 respectively are spaced and tapered valve plugs 10' and 16'. Suitable ears 17-17 permit the attachment of this valve structure to a suitable support.

The foregoing description has been relative to the structure shown in our copending application and the following description will be relative to the improved part of the mechanism.

The bonnet which has been generally referred to by 13, consists of a polygonal shaped head 18, provided with a depending and externally threaded apron 14. A shoulder 20 is provided between the apron 19 and the head 18 for abutment against the upper end of the cylinder 7. The bonnet is provided with a hub structure 21, through which the valve stem 15 is slidably disposed and the packing gland 23 carried by the bonnet is provided for the stem 15. A compressible spring 23' is interposed between the bonnet 13 and the uppermost valve element 10', for urging the valve stem downwardly when the latter is released by the actuation of the slide plate 24. The slide plate 24 is of elongated extent as shown in Figure 2, and is provided with an ovate opening 25. An inclined construction 26 on the top surface of the plate has its lower end merging with the edge of the opening 25, and upon this inclined surface, the lower end of the stem 15 is adapted to normally rest. The plate 24 is supported upon the rollers 27-27 and is slidable through an opening 28 in the side of the cylinder 27.

A pair of flanges 29-29 extend laterally at one side of the cylinder 7 and between these flanges are rotatably mounted the gear 30 and the pinion 31. The pinion 31 is carried by the pin 32, while the gear 30 is mounted on the shaft 33.

An arm 34 projects from the pinion 32 and is equipped with an adjustable float 35 at its free end. The portion of the slide plate 24 protruding beyond the side of the cylinder 7 is provided with a plurality of longitudinally

spaced openings 36 for receiving the teeth of the gear 30. Thus, when the oil in the tank rises, the stem 15 will be released, thus closing the valve 16' and opening the valve 10'. A dome-shaped cover 37 is provided, at its edge portion with bayonet slots 38 for engagement with the pins 39' on the upper end portion of the cylinder 7. The cover is also provided with a handle 39, whereby it may be actuated in attaching or detaching the same from the valve structure.

A wrench, such as is generally referred to by 40 consists of a handle 41', with a tubular shank 42 extending therefrom. The shank is provided with a head 43 at its free end and a pair of projections 44—44 depending therefrom. The shoulder is adapted to be inserted within the cylinder after the bonnet 13 has been removed and is engageable in the recesses 45 of the valve seat, so that the latter may be easily removed. The shank portion 42 of the rim is to receive the valve stem while in the act of removing the valve seat.

It will thus be seen that the present invention embodies numerous improvements over our copending application and over the art, and it is to be understood that various changes in the shape, size, and materials may be resorted to, without departing from the spirit or scope of the invention as claimed hereinafter.

What is claimed is:

1. In a valve structure including a body, an inlet and an outlet, a slidable valve stem within the body, valve seats, valve heads on the stem for engagement on said seats, a slide plate upon which the stem is normally adapted to rest for maintaining one of the valve heads seated, said plate being formed with an opening through which the stem may gravitate to unseat the last mentioned valve head and to seat the other valve head, a float, and gear means between said float and said plate whereby said plate may be slid to permit the gravitation of said valve stem at a predetermined liquid level.

2. In a valve structure including a body, an inlet and an outlet, a slidable valve stem within the body, valve seats, valve heads on the stem for engagement on said seats, a slide plate upon which the stem is normally adapted to rest for maintaining one of the valve heads seated, said plate being formed with an opening through which the stem may gravitate to unseat the last mentioned valve head and to seat the other valve head, a float, and gear means between said float and said plate whereby said plate may be slid to permit the gravitation of said valve stem at a predetermined liquid level, said gear means consisting of a pair of flanges projecting from the side of the valve body, an arm extending from the float, a pinion on the arm, a gear for meshing with the pinion, and openings at one end of

the slide plate with which the gear is adapted to mesh.

3. In a valve structure including a body, an inlet and an outlet, a slidable valve stem within the body, valve seats, valve heads on the stem for engagement on said seats, a slide plate upon which the stem is normally adapted to rest for maintaining one of the valve heads seated, said plate being formed with an opening through which the stem may gravitate to unseat the last mentioned valve head and to seat the other valve head, a float, and gear means between said float and said plate whereby said plate may be slid to permit the gravitation of said valve stem at a predetermined liquid level, and a cover for the upper end of the valve structure.

In testimony whereof we affix our signatures.

OLIVER MORGAN.
JOHN W. STARK.
